[57] CLAIM

The ornamental design for a knob for the lid of a cooking pot, as shown and described.

DESCRIPTION

FIG. 1 is a top perspective view of a knob for the lid of a cooking pot showing my new design;

FIG. 2 is a top plan view thereof;

FIG. 3 is a side elevational view thereof with the sides not shown being similar to the side shown; and

FIG. 4 is a bottom plan view thereof.

The center of the knob for the lid of a cooking pot in FIGS. 1 and 2 has been lined to indicate color.
